UNITED STATES PATENT OFFICE

ROBERT MARTIN CHAMBERS, OF FINAGHY, BELFAST, IRELAND, ASSIGNOR TO GEORGE MARTIN AND TERESA MARTIN, BOTH OF BELFAST, IRELAND

DEPOSITING MACHINE FOR DOUGH, SEMIFLUID, PASTY, OR LIKE MATERIALS

Application filed February 7, 1931, Serial No. 514,244, and in Great Britain March 26, 1930.

This invention relates to machines for depositing semi-fluid or pasty material or materials such as dough and other baking mixtures.

5 In such machines a bulk supply of the plastic material from which quantities are to be discharged is contained in a container means, and valve means is provided for controlling the discharge of quantities of the 10 material by ejector means.

According to this invention an intermittent motion is imparted to the ejector means such that, during the operation of the valve means, a dwell period is provided in which 15 the ejector means is stationary, means being provided whereby the extent of movement of the ejector means can be varied so as to vary the quantities of material ejected thereby, and control means being provided for adjusting the time of closing of the valve means so that when the valve means closes, the 20 ejector means is always at the same stage in its operation irrespective of variations in the extent of movement of the ejector means.

25 The invention will now be described, by way of example, with reference to the annexed drawings, in which,

Fig. 1 is an end elevation of a power driven depositing machine in accordance with the 30 invention;

Fig. 2 is a general front elevation of the depositing machine, partly in section to show the plunger and cylinder and the valve;

Fig. 3 is a sectional detail view of the quadrant lever 38 and its connection with the gudgeon block 47;

Fig. 4 is an enlarged detail elevation of the gearing whereby a "pause" is given to the plungers while the valve operating cam is 40 opening the valves;

Fig. 5 is another enlarged detail view of the gearing shown in Fig. 4, the gearing in this case being shown in plan;

Fig. 6 is a diagrammatic view, showing different positions of the valve operating gear for different adjustments of the quadrant lever to give different strokes of the plungers;

Fig. 7 is a similar diagrammatic view of another position of the quadrant lever and valve controlled gear;

Figs. 8 and 9 are additional sectional detail views showing the plunger and valve in different positions.

Referring to the drawings,

The hopper 27 for containing the material to be deposited is fitted on top of a casting 28 containing the cylinders 29, the tops of which open into the bottom of the hopper 27. The plungers 30 are connected to a top moving beam 31 in each end of which is a fixed guide bar 32 working in guides in brackets 33 attached to the casting 28 containing the cylinders 29. The guide bars 32 have racks cut on them which are each engaged by segment wheels 34 (see Fig. 1) keyed or otherwise attached to a rocking shaft 35 and imparting an equal motion to each end of the beam 31. The rocking shaft 35 takes its motion from the crank 36 and connecting rod 37 acting on a quadrant lever 38 attached to the rocking shaft 35. As the crank 36 passes over the "dead" center at the end of the down stroke of the beam 31, the motion of the plungers 30 during the time the valves 39 in the valve plate 39^a are closed, is so small as to be negligible. It is therefore unnecessary to make special provision for a "pause" or "dwell" at this point as in hand operated machines. On the down stroke, however, provision is made for a "pause" or "dwell" in the motion of the 50 plungers 30 just as they are entering the top of the cylinders 29 (see Fig. 2). To secure this, the crank 36, instead of being keyed directly on the main shaft 40 which has a continuous motion and to which the cam 41 for opening the valves 39 is keyed, is driven through a chain of four gears, consisting of two equal engaging gears 42 and 43 (Fig. 5) of which the driver 42 is keyed on the main shaft 40 and the driven wheel 43 is keyed on 55 a counter-shaft 44. The second pair of gears comprises a segment wheel 45 which is the driver and is keyed on the counter-shaft 44. The segment wheel 45 engages, intermittently, the pinion wheel 46 keyed on the boss of the crank 36 which is free to revolve independently on the main shaft 40, but having an intermittent motion imparted to it by the chain of gearing hereinbefore described.

The number of effective teeth on the segment 60

wheel 45 are equal to those in the pinion wheel 46, so that the crank 36 will give a revolution for each revolution of the main shaft 40 and cam 41 hereinbefore described, the crank 36 and the cam 41 being always in the same relative position to each other, immediately before the "pause" of the crank begins as shown in the detail views Figs. 4 and 5 where the segment wheel 45 is just disengaging the pinion wheel 46 causing a "pause" in the motion of the crank 36 during which the valves 39 are opened by the valve controlling cam 41 hereinbefore mentioned, the cam moving so that its point of contact with the roller 62^b 10 travels from the point U to the point V. The relative positions of the cam 41 and the crank 36, at the end of the "pause" are shown in Fig. 1. After the "pause" due to the gap in the segment wheel 45, the segment wheel 45 again engages the pinion wheel 46, driving the crank 36 one revolution and overtaking the cam 41, bringing the crank 36 and the cam 41 into the same relative position shown in Figs. 4 and 5 when the next "pause" 20 begins. A suitable interlocking device is provided to ensure that the teeth of the segment wheel 45 will properly register with those in the pinion wheel 46 when re-engaging. In the example shown this is provided 25 for by providing a portion of a cylindrical face 45^a concentric with the segment wheel 45 and attached to it, the pinion wheel 46 having a locking piece 46^a attached to it with a hollow face 46^b and struck from the same center as the segment wheel 45 when the crank 36 is at the "pause" position. The arc-shaped portion 45^a engages the locking piece 46^a when the teeth of the segment wheel 45 and the pinion wheel 46 are disengaged, 35 thereby preventing the pinion wheel 46 from moving while the locking member 46^a engages the member 45^a.

A quadrant lever 38 attached to the rocking shaft 35 is struck with a radius equal to 45 the length of the connecting rod 37 and is so set that when the plungers 30 are just entering the cylinders 29, with the crank 36 at the "pause" position, the centre of the curve of the quadrant 38 coincides with the centre 36^a 50 of the crank pin so that the relative positions of the valves and plungers at this point is constant for all positions of an adjustment block 47. The adjustment block 47 is slideable on the quadrant lever 38, the gudgeon pin 37^a of the connecting rod 37 being formed on the block 47, which will hereinafter be called the gudgeon block 47. The gudgeon block 47 is adjustable along the quadrant 38 by means of a hand wheel 47^a which operates 55 a bevel pinion 48 engaging teeth 38^a cut on the face of the quadrant 38 (see Fig. 3). The rim of the hand wheel 47^a and the face of the quadrant lever 38 are provided with numbers or indexes, whereby a record of any setting 60 can be kept. A locking screw 49 is provided

by which the pinion 48 can be moved along its axis and, acting as a wedge, locks the block 47 firmly on the lever quadrant 38. As shown in detail at Fig. 3 the pinion 48 is surrounded by the bush 50 which internally is a hollow cone fitting the pinion 48 and externally cylindrical to fit in the casting 51. Part of the bush 50 is cut away to allow the teeth 38^a of the quadrant lever 38 to pass through and engage with those in the pinion 48. The bush 50 is adjustable axially in the casting 51 by the ring 52 threaded in the casting 51 and through which the hollow stem 53 of the bush 50 passes and in which it is secured by the fixed collar 54. The bush 50 is prevented from turning in the casting 51 by the key screw 55 engaging a slot in the bush 50. The hollow shank 53 is tapped to receive the locking screw 49. The pinion 48 is preferably cut integral with the hollow stem 57 through which the locking screw 49 passes. The locking screw 49 is free to turn in the pinion 48, but is retained axially at the pinion end by the fixed collar 54 and at the other end by the face of the thumb control 49^a secured to the locking screw 49. The thumb control 49^a is for the purpose of revolving the screw 49. It will be obvious that when the locking screw 49 is screwed inwards it will carry the pinion 48 with it and using it as a wedge will bring it into the position shown by the dotted lines in Fig. 3, forcing the quadrant lever 38 against the faces of the casting 51. The bush 50 is so adjusted by means of the threaded ring 52 that, coinciding with the above mentioned wedge action, the conic surfaces of the pinion 48 and the bush 50 will act on each other as a powerful clutch and will prevent the pinion 48 from turning. The ring 52 100 can then be locked by the screw 56. To prevent the adjusting screw 49, when screwed outwards, from locking the face of the pinion 48 against the casting 51, two lock nuts are provided at 57 and are so adjusted and locked on the screw 49 that when the adjusting screw 49 is screwed fully out, withdrawing the pinion by means of the collar 54, these nuts will engage the face of the part 53, leaving a certain amount of working clearance 110 between the face of the pinion 48 and the casting 51. The hand wheel 47^a is keyed on the stem 57^a and has preferably index teeth cut on its face 47^b and an index finger 58 fixed on an arm of a collar 59 which retains the connecting rod 37 on the gudgeon pin 37^a to 115 which it is fixed by a screw and steady pin. The index finger 58 engages teeth 47^c in the periphery of the hand wheel 47^a as the locking screw 49 is being screwed in and preventing the index wheel 47^a from turning while the locking screw 49 is being tightened up. When the locking screw 49 is screwed fully out, the hand wheel or index wheel 47^a is in 120 the position shown in Fig. 1 with its rim clear of the index finger 58, the dotted lines 125

indicate the position when fully tightened up.

It will be obvious that when the gudgeon block 47 is at the top of the quadrant 38, the longest stroke of the plungers 30 will be secured and, conversely, with the gudgeon block 47 at the bottom of the quadrant lever 38 the shortest stroke of the plungers will be obtained. Any particular setting of the gudgeon block 47 on the lever 38 will give a corresponding definite stroke to the plungers 30 and will therefore measure off a definite amount of the material from the hopper 27. The material is prevented from flowing down through the cylinders 29 while the valves 39 are open by reason of the plungers 30 forming plugs in the tops of the cylinders.

The valve gear is shown more particularly in Figs. 2, 8 and 9. The valves 39 are of the sliding type, the valve plate 39^a acting in connection with all the cylinders 29 and controlled as to opening by the cam 41 (see Figs. 1 and 4) and as to closing by a rocking cam 60 (see Fig. 1 and also Figs. 6 and 7). The rocking cam 60 is pivoted on an extension of the connecting rod 37 at 36^a near one end and controlled by a link 61 pivoted to the frame of the machine at 61^a and preferably, as shown, at the pivot of the T-shaped lever 62. The T-shaped lever is an inverted T-shape with the long arm upwards and the cross arm underneath, it is pivoted to the frame at 61^a at the intersection of the vertical arm with the cross piece. The long arm 62^a is forked (see Figs. 1 and 2), with a roller 62^b on one end of the fork bearing on the cam 41 for opening the valves 39 and another roller 62^c on the other end of the fork engaging on the cam plate 60 intermittently, the object being to control the closing of the valves 39 so that the closing of the valves will always take place at the end of the down stroke of the plungers 30, which end of stroke obviously varies as the gudgeon block 47 is moved up or down the quadrant lever 38. One end 62^d of the lever 62 is attached to a spring 63 which holds the rollers 62^b and 62^c respectively in contact with the cam 41 or the rocking cam plate 60 while the other end 62^e of the T-shaped lever is connected by a link 64 with the rocking arm 65 controlling the valve lever 66.

The relative position of a plunger 30 and valve opening 39 are shown in three positions at Figs. 2, 8 and 9. Fig. 2 shows the valve 39 fully open with the plunger 30 at the end of the "pause" period. Fig. 8 shows the valve 39 fully closed, with the plunger 30 completely withdrawn from the cylinder 29 and at the top of its stroke. Fig. 9 shows the plunger 30 at the beginning of the "pause" period and the valve 39 just beginning to open. Fig. 9 corresponds with the position of the gearing and cam as shown at Figs. 4 and 5.

Figs. 6 and 7 are diagrammatic views which

have been provided in order to illustrate the automatic action of the cam plate 60 in securing automatic adjustment of the time of closing the valve 39 to coincide with the crank 36 passing the dead centre, when the plunger 30 is at the lower end of its stroke and notwithstanding any altered angular position of the crank 36 at which the dead centre occurs when the position of the gudgeon pin 37^a is altered on the quadrant lever 38 to adjust the stroke of the plunger 30 to suit the different sizes of deposits as may be required. The difference in angular position of the crank dead centre is shown in Fig. 7 by the angle between the lines A and B. Fig. 6 shows the longest stroke of the piston 30 with the gudgeon pin 37^a on the quadrant lever 38 as near to the rocking shaft 35 as possible and giving the greatest motion to the plunger 30 and the largest deposit. Fig. 7 shows the gudgeon pin 37^a well down on the lever 38 and giving a short stroke to the plunger 30 and consequent small deposit. When the gudgeon pin 37^a is at the end of the lever 38, the roller 62^b follows the cam 41 and the cam plate 60 does not come into action. Varying positions of the parts are indicated at Figs. 6 and 7, the close dotted lines indicate the first position, the full lines indicate the second position and the chain dotted lines indicate the third position. The relative positions of the piston 30 and the quadrant lever 38 do not coincide in both Figs. 6 and 7 on account of the difference in the stroke. In Fig. 7, the roller 62^b is just leaving the cam 41 with the cam plate 60 taking charge. As these are only diagrammatic drawings, for the sake of clearness and easy reference, the valve gear, which should be at right angles to the rest of the drawings, is shown in the same plane. The valve gear is omitted in Fig. 7, as it will be clearly understood from Fig. 6.

The roller 62^b is shown in Fig. 6 leaving the cam 41 and the rocking cam or cam plate 60 taking charge of the roller 62^c on one arm of the fork lever 62^a as the crank pin comes to the position shown at 36^a, the rocking cam or cam plate 60 being under the control of the pin 36^a on the extension of the connecting rod 37 beyond the crank pin 36^a and the link 61 which is centered at the other end to the frame of the machine at 61^a. At this point the valve 39 is open and the plunger 30 occupies the position 30^a in Fig. 6, the quadrant lever 38 occupying the position shown in dotted lines at 38^a Fig. 6. The cam plate 60 holds the roller 62^c with the lever 62^a at the same position and with the valve 39 still open until the quadrant lever 38 moves to the position shown in full lines at Fig. 6 and Fig. 7, the crank and connecting rod having moved to the position shown in full lines when the cam plate 60 will also be in the position shown in full lines. The crank is, at

this position, approaching the dead centre and the quadrant 38 and the plunger 30 are practically stationary, until the crank reaches the point 36^c, but while the crank is moving from the position 36^c to the position 36^r the cam plate 60 has moved from the position shown in full lines to the position shown in chain dotted lines at 60^a, the roller 62^a following it under the action of the spring 63, and moving the lever 62^a from the position shown in full lines to the position shown in chain dotted lines and acting through the link 64 on the rocking arm 65, moving it from the position shown in full lines to the position shown in dotted lines, carrying with it the lever 66 and closing the valve 39 through the link 39^b moving the valve from the open position shown in full lines to the closed position shown in dotted lines Fig. 6. The angle between the lines C and C¹ indicates the total angular travel of the quadrant 38 for the largest deposit as shown at Fig. 6, whilst the angle between the lines D and D¹ indicates the angular travel of the quadrant 38 when making the smaller deposit according to the adjustment of the gudgeon pin 37^a on the quadrant lever 38, as shown in Fig. 7. The angle between the lines A and B, shows the difference in angle of the crank when on the dead centre in each case.

The operation of the apparatus is briefly as follows:—

Commencing with the up stroke of the plungers 30 under the action of the quadrant 38 and connecting rod 37, it will be apparent that the valve 39, which has initially been closed at the end of the preceding down stroke by the spring 63 acting through the lever 62, link 64, arm 65, lever 66 and link 39^b, is kept closed by the action of the said spring 63 until the plungers 30 reach the top of their stroke and have moved a short distance through their down stroke to the position shown in Fig. 2. As will be understood, the plastic material from the hopper 27 enters the cylinders 29 during the upward and downward movement of the plungers 30 above the level of the open upper end of the cylinder 29. The "pause" or "dwell" in the motion of the plungers 30 then ensues while they are in the position shown in Fig. 2, this result being coincident with the movement of the gap portion of the segment wheel 45 over the teeth of the wheel 46, by reason of which gap the result in question is caused. As hereinbefore stated, the opening of the valves 39 takes place in the interval provided by the said "pause" or "dwell", each valve being moved by the action of the cam 41 operating through the roller 62^b, T-shaped lever 62, link 64, arm 65, lever 66 and link 39^b. At the end of the "pause" or "dwell", the downward stroke of the plungers 30 is continued by the crank 36, connecting rod 37 and quadrant lever 38. The valves 39 remain open

during the down stroke of the plungers 30 until the plungers 30 under the action of the quadrant lever 38 almost reach the bottom of their stroke. At this point, the cam 41 has rotated free of the roller 62^b, so that the T-shaped arm 62 turns under the action of the spring 63 until the roller 62^a comes into contact with the cam plate 60. By this movement, the valves 39 are closed through the intermediary of the link 64, arm 65, lever 66, and link 39^b, the instant of closing of the valves 39 being determined by the position of the cam plate 60, which position, in turn, varies automatically with the adjustment of the stroke-adjusting connecting rod 37 in virtue of the connection of the cam plate 60 with this connecting rod through the pin 36^a on the extension of this rod. This completes the cycle of operations taking place during each revolution of the main shaft 40, and, the quantity of plastic material entering the cylinder 39 having been completely ejected by the plungers 30 during their down stroke, the said cylinders are ready to receive a further charge of material, on the plungers 30 again moving to the upper end of their stroke.

It will be understood that the invention is applicable to machines for depositing or ejecting quantities of any viscous, liquid, granular or other substance, such as cake mixtures, jam or flour, and any other substances capable of flowing from a bulk supply into individual ejector vessels or cylinders, all such substances being hereinafter referred to, for convenience, as "plastic material."

I claim:—

1. A machine for depositing quantities of plastic material from a bulk supply thereof, comprising a trough for said bulk supply, a plurality of cylinders communicating with said trough, plungers for ejecting material entering said cylinders from said trough, valve means for controlling the discharge of said quantities from said cylinders, actuating means for said valve means, operating means adapted to operate said plungers, a toothed wheel, means for rotating said toothed wheel uniformly, a toothed segment having the same number of teeth as said toothed wheel and a gap in the pitch circle thereof, and transmission mechanism between said toothed segment and said plungers whereby an intermittent motion is imparted to said plungers such that during operation of said valve means a pause occurs in the operation of said plungers.

2. A machine for depositing quantities of plastic material from a bulk supply thereof, comprising a trough for said bulk supply, a plurality of cylinders communicating with said trough, plungers for ejecting material entering said cylinders from said trough, valve means for controlling the discharge of said quantities from said cylinders, a swing-

ing lever adapted to reciprocate said plungers, a crank for oscillating said lever, means for periodically imparting to said crank a complete turn alternating with a dwell period wherein said crank is stationary, a rotatable cam, operating means for driving said cam, lever mechanism operable by said cam so as to open said valve means, spring means for closing said valve means, and a control plate for timing the closing of said valve means by said spring.

3. A machine for depositing quantities of plastic material from a bulk supply thereof, comprising a trough for said bulk supply, a plurality of cylinders communicating with said trough, plungers for ejecting material entering said cylinders from said trough, valve means for controlling the discharge of said quantities from said cylinders, a swinging lever adapted to reciprocate said plungers, a rotatable crank, means for periodically imparting to said crank a complete turn alternating with a dwell period wherein said crank is stationary, a rotatable cam, operating means for rotating said cam continuously, lever mechanism operable by said cam so as to open said valve means, spring means for closing said valve means, a control plate for timing the closing of said valve means by said spring means, a connecting rod for transmitting motion from said crank to said swinging lever, means whereby connection between said swinging lever and connecting rod is adjustable, and means for locking said swinging lever and connecting rod in their adjusted position.

4. A machine for depositing quantities of plastic material from a bulk supply thereof, comprising a trough for said bulk supply, a plurality of cylinders communicating with said trough, plungers for ejecting material entering said cylinders from said troughs, valve means for controlling the discharge of said quantities from said cylinders, a swinging lever adapted to reciprocate said plungers, a crank for oscillating said lever, means for imparting periodically to said crank a complete turn alternating with a dwell period wherein said crank is stationary, a rotatable cam, operating means for rotating said cam continuously, lever mechanism operable by said cam so as to open said valve means, spring means for closing said valve means, means whereby the extent of movement of said plungers can be varied so as to vary the quantities ejected thereby, a spring for closing said valve means, a control plate for limiting movement of said valve means by said spring, and means whereby said control plate is pivotally connected with said crank so that said valve means closes said cylinders when said plungers are at the same stage of their periodic motion, irrespective of variations in the extent of movement of the plungers.

5. A machine for depositing quantities of plastic material from a bulk supply thereof, comprising a trough for said bulk supply, a plurality of cylinders communicating with said trough, plungers for ejecting material entering said cylinders from said trough, valve means for controlling the discharge of said quantities from said cylinders, actuating means for said valve means, operating means adapted to operate said plungers, a toothed wheel, means for rotating said toothed wheel uniformly, a toothed segment having the same number of teeth as said toothed wheel and a gap in the pitch circle thereof, means for preventing movement of said toothed wheel when disengaged at said gap from the teeth of said toothed segment, and transmission mechanism between said toothed segment and said plungers whereby an intermittent motion is imparted to said plungers such that during operation of said valve means a pause occurs in the operation of said plungers.

6. A machine for depositing quantities of plastic material from a bulk supply thereof, comprising a trough for said bulk supply a plurality of cylinders communicating with said trough, plungers for ejecting material entering said cylinders from said trough, valve means for controlling the discharge of said quantities from said cylinders, a swinging lever adapted to reciprocate said plungers, a rotatable crank, means for imparting periodically to said crank a complete turn alternating with a dwell period wherein said crank is stationary, a rotatable cam, operating means for rotating said cam continuously, lever mechanism operable by said cam so as to open said valve means, spring means for closing said valve means, a control plate for timing the closing of said valve means by said spring means, a connecting rod for transmitting motion from said crank to said swinging lever, means whereby connection between said swinging lever and connecting rod is adjustable, means for locking said swinging lever and connecting rod in their adjusted position, and means whereby said control plate is pivotally connected with said crank so that said valve means closes said cylinders always when said plungers are at the bottom of their stroke irrespective of variations in the length of said stroke.

7. A machine for depositing quantities of plastic material from a bulk supply thereof, comprising a trough for said bulk supply, a plurality of cylinders communicating with said trough, a plunger for each cylinder adapted to eject material entering therein from said trough, a valve for each cylinder adapted to control discharge of material therefrom, inter-connecting means whereby said plungers are adapted to move in unison, a swinging arc shaped lever adapted to reciprocate said plungers, a rotatable crank, 130

means for periodically imparting to said crank a complete turn alternating with a dwell period wherein said crank is stationary, a rotatable cam, operating means for rotating said cam continuously, mechanism operable by said cam so as to open said valve means, spring means for operating said mechanism to close said valve means, a control member for timing the closing of said valve means by said spring means, a connecting rod for transmitting motion from said crank to said swinging lever, means whereby connection between said swinging lever and connecting rod is adjustable to vary the stroke of said 10 plungers, and wedge means for locking said swinging lever and connecting rod in their adjusted position.

In testimony whereof I affix my signature.

ROBERT MARTIN CHAMBERS.
